(57) **CLAIM**

The ornamental design for an instrument pick, as shown and described.

DESCRIPTION

FIG. 1 is a front perspective view of an instrument pick in accordance with the present invention;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

Any shading or hatching are not features of the design and are merely utilized to illustrate surface contours of the design in the drawings. The broken lines depict portions of the instrument pick that form no part of the claimed design.

1 Claim, 6 Drawing Sheets
